UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF MICHIGAN.

LAMP.

1,202,058.

Specification of Letters Patent. Patented Oct. 24, 1916.

Application filed May 6, 1916. Serial No. 95,758.

To all whom it may concern:

Be it known that I, CHARLES E. GODLEY, a citizen of the United States, and residing at Detroit, in the county of Wayne and State of Michigan, have invented a new and Improved Lamp, of which the following is a specification.

This invention relates to lamps of the headlight type, particularly to those adapted for motor vehicles, and its object is to provide means whereby the direction of the beam of light projected by the reflector may be varied without moving the body of the lamp.

This invention consists, in combination of the body of the lamp which is preferably cup-shaped; a reflector therein, of means for pivotally mounting the reflector in the body, the pivotal axis being preferably at the open ends of the reflector and body and central therewith, and a lens and lens ring closing the open end of the reflector.

It also consists in providing resilient means for restraining the reflector from turning on its pivots.

It further consists in means for swinging the reflector relative to the body of the lamp.

In the accompanying drawings, Figure 1 is a central longitudinal vertical section of a lamp embodying this invention. Fig. 2 is a diagrammatic view of the front end of a motor vehicle indicating mechanism for moving the reflector. Fig. 3 is a front elevation of sections of portions of the body and of the reflector of the lamp, parts of the body and lens ring being broken away to disclose the pivots of the reflector. Fig. 4 is a transverse section of the retaining spring and Fig. 5 is a longitudinal section thereof. Fig. 6 is a transverse section of the edge of the reflector and the lens ring.

Similar reference characters refer to like parts throughout the several views.

Referring to Fig. 1, the body 1 of the lamp is shown connected to the tubular support 2 into which the usual socket 3 extends. The reflector 4 carries a thimble 5 in which a socket sleeve 6 is slidable. A lamp-bulb 7 is mounted in this sleeve and a flexible connector 8 extends from the socket 3 to the sleeve 6. These parts are of any well known construction.

The front of the lamp-body 1 turns inwardly to constitute a substantially cylindrical band 9 and a radial flange 10. If de-

sired, this band 9 may be formed at intervals with circumferential corrugations or teeth 11. The reflector 4 is formed with a radial portion 12, preferably grooved to receive the packing ring 13 of cotton, rubber or other suitable material, and with a cylindrical flange 14 at the outer edge of the part 12. At intervals along the part 12, the tongues 15 are struck up, as indicated in Fig. 6, to position the lens 16.

The lens ring 17 has a radial flange portion 18 that presses against the lens 16. To hold this lens and lens ring in position any desirable means may be employed, but I prefer a resilient rod or wire 19, secured at intervals to the reflector by spots 20 of solder, or by welding. This wire is formed at intervals with ears 22 that snap over the outer edge of the radial flange 18 of the lens ring and thus resiliently hold the lens ring and lens in position. Any other desired construction of lens ring may be employed.

The connection between the reflector and the body may be by means of pivots making any desired angle with the horizontal, the pivots 25 shown in Fig. 3 being in a vertical line and those in Fig. 1 being in a horizontal line. The cylindrical part 14 of the reflector may be formed with two holes to receive the screws 24, the holes being surrounded by the bearing flanges 25. A nut 26 to receive each screw is mounted in the flange 9 of the body, and diametrically opposite each other so that the rear end of the reflector can be swung on these screws as an axis to deflect the beam of light as desired.

Various means may be employed to hold the reflector in position. Circumferentially corrugated springs 27, positioned half way between the pivots and mounted on the cylindrical flange 14 of the reflector, as shown in Fig. 3, may have corrugated surfaces, as shown in Fig. 4, to fit the circumferentially corrugated portions of the flange 9 of the body. The tension of these springs is such that considerable force is required to swing the reflector within the body.

While the reflector can be positioned by pressing directly upon it or upon the lens ring, means may be provided to move the reflector relative to the body from a distance, as from the seat of the vehicle. The manner indicated in Figs. 1 and 2 consists in mounting an actuating member within reach of the person operating the vehicle,

a small lever 29 being shown mounted on the steering post 30. A cord 31 extends to the lamp and connects to a sleeve 32 which is secured to the reflector by means of the screw 33.

Opposite the screw 33 is an ear 34 to which a strong spring 35 connects which spring is anchored at its inner end to the body of the lamp at 36. This spring must 10 be strong enough to overcome the resistance of the resilient clamps 27, although these may be omitted entirely when the deflecting device just described is employed.

Many changes in the details of construction 15 may be made by those skilled in the art without departing from the spirit of my invention as set forth in the following claims.

I claim:

1. In a lamp, the combination of a body, 20 a reflector therein, a lens and lens ring mounted on the reflector, a lamp-bulb carried by the reflector, a pair of pivots between the body and the reflector to permit the reflector to be swung thereon within the body, and resilient means on the reflector 25 engaging said body to restrain the movement of the reflector within the body.

2. In a lamp, the combination of a cup-shaped body, a cup-shaped reflector therein, 30 pivots carried by the body at its open end on which the reflector is pivotally mounted, a lens and lens-ring to close the open end of the reflector, manually operable means to swing the reflector in the body in one direction, and a spring to swing the reflector in 35 the opposite direction.

3. In a lamp, the combination of a cup-shaped body, a cup-shaped reflector therein, pivots carried by the body at its open end 40 on which the reflector is pivotally mounted,

a lens and lens-ring to close the open end of the reflector, manually operable means to swing the reflector in the body in one direction, a spring to swing the reflector in the opposite direction, and a second spring to 45 restrain the movement of the reflector in either direction.

4. In a lamp, the combination of a cup-shaped body having an inturned cylindrical portion, a cup-shaped reflector within the body having its outer edge in the form of a cylindrical flange positioned within the cylindrical portion of the body, pivots between said cylindrical parts of the body and reflector, a circular lens mounted with- 50 in the cylindrical flange of the reflector, a lens-ring in engagement with said lens, and means on the reflector for resiliently holding the lens-ring and lens in position.

5. In a lamp, the combination of a body, 55 a reflector therein, a lamp-bulb carried by the reflector, a pair of pivots between the lamp body and the reflector to permit the reflector to be swung thereon within the body, and yieldable means between the body 60 and the reflector to restrain the movement of the reflector within the body at all times irrespective of the relative positions of the body and reflector.

6. In a lamp, the combination of a cup-shaped body having an inturned cylindrical portion, a cup-shaped reflector within the body having its outer edge in the form of a cylindrical flange positioned within the cylindrical portion of the body, pivots between 70 said cylindrical parts of the body and reflector, and means for restraining the reflector from moving from the positions to which it may be swung on said pivots.

CHARLES E. GODLEY.
